DESIGN FOR A CIGARETTE LIGHTER

Harry Negbaur, New York, N. Y.

Application March 29, 1944, Serial No. 113,066

Term of patent 14 years

(Cl. D48—27)

To all whom it may concern:

Be it known that I, Harry Negbaur, a citizen of the United States of America and a resident of New York, in the county of New York and State of New York, have invented a new, original, and ornamental Design for a Cigarette Lighter, of which the following is a specification, reference being had to the accompanying drawing, forming a part thereof.

In this drawing:

Figure 1 is an illustration in side elevation of a cigarette lighter, showing my new design, with the base and cap or cover member separated; and

I claim:

The ornamental design for a cigarette lighter, as shown and described.

HARRY NEGBAUR.
